an US patent of 2,615,427 issued to the inventor of this application, which is a pencil actuated sharpener having a slot in the upper end of an elongated casing and sharpening elements mounted in the slot, which slot has a slot in the upper end of the slot, and which slot is 20

1.58 mm. wide, 1.5 mm. high and 4.5 mm. wide, the slot being positioned in the slot so that the pencil will be held in the slot and the slot will be able to rotate with the slot.

UNITED STATES PATENT OFFICE

2,615,427

PENCIL ACTUATED PENCIL SHARPENER

William R. Lehmann, Atlanta, Ga.

Application February 6, 1951, Serial No. 209,620
3 Claims. (Cl. 120—96)

This invention relates to pencil sharpeners of the type in which the crank or handle is eliminated and in which the sharpening elements are actuated by a pencil inserted therein, and in particular this invention relates to an improved pencil sharpener having rotatable sharpening elements slidably mounted in an elongated casing wherein a pencil inserted through a slot in the casing and into the said sharpening elements actuates the elements for sharpening the pencil as the pencil is reciprocated in the casing.

The purpose of this invention is to provide a pencil sharpener that may be positioned in or mounted on a drawer of a desk or permanently attached to the edge of a table or desk top and in which means is provided for actuating the sharpener without a handle or crank projecting therefrom.

Various types of pencil sharpeners have been provided without cranks or handles but the conventional pencil sharpener of this type is held in the hand and the pencil turned therein. In the type of pencil sharpener having a crank or handle the sharpener is attached by screws or the like to a desk or table top, window frame or sill, or to a cabinet and it is objectionable to place screw holes in furniture or window frames, for this purpose. With this thought in mind this invention contemplates an elongated casing having pencil sharpening elements with gears thereon positioned with the gears meshing with racks whereby with the pencil held therein and moved in either direction the sharpening elements are actuated to sharpen the pencil.

The object of this invention is, therefore, to provide means for forming a pencil sharpener whereby the sharpener may be permanently installed in the outer edge of a desk drawer or the like.

Another object of the invention is to provide means in a pencil actuated pencil sharpener whereby the sharpening elements rotate in the same direction with a holder moved back and forth along the rack of the sharpener.

Another object of the invention is to provide a pencil sharpener in which a pencil inserted in and reciprocated in an elongated slot provides the actuating means of the sharpener.

A further object of the invention is to provide a pencil sharpener adapted to be mounted against the inner surface of the outer end of a drawer or desk and which is operated by moving a pencil back and forth therein, which is of a simple and economical construction.

With these and other objects and advantages

which will be apparent as the following description proceeds, the invention may be understood to be a pencil sharpener having an elongated casing having a slot in the upper end of the slot having a slot in the upper end of the slot, and which slot has a slot in the upper end of the slot, and which slot is 20

1.58 mm. wide, 1.5 mm. high and 4.5 mm. wide, the slot being positioned in the slot so that the pencil will be held in the slot and the slot will be able to rotate with the slot.

2,615,427

in view the invention embodies an elongated casing substantially rectangular shaped in cross section having a slot in the upper end and having gear racks on opposite sides of the slot, and pencil sharpening elements slidably mounted in the casing, positioned to receive the point of a pencil, and having means thereon for rotating the sharpening elements as the elements are reciprocated by a pencil, the point of which is inserted therein.

Other features and advantages of the invention will appear from the following description taken in connection with the drawings wherein:

Figure 1 is a longitudinal section through the improved pencil sharpener, with parts broken away, showing the sharpening elements and mounting and actuating parts in elevation therein.

Figure 2 is a cross section through the pencil sharpener shown in Fig. 1 showing a pencil positioned in the sharpening elements.

Figure 3 is a similar section with the sharpening elements shown in elevation.

Figure 4 is a sectional plan through the improved pencil sharpener showing the latch means for retaining a gear therein in inoperative position whereby the gear actuates the sharpening elements with the elements traveling in one direction and releases the sharpening elements with the elements traveling in the opposite direction.

Figure 5 is a similar view showing the gear for operating the sharpening elements with the sharpening elements moving in a direction opposite to that shown in Fig. 4.

Figure 6 is a view showing an upper spacing washer fitted between the gears on the sharpening elements.

Figure 7 is a similar view showing the lower spacing washer.

Figure 8 is a detail showing the slides in which the lower ends of the sharpening elements are journaled.

Figure 9 is a detail showing an upper guide sleeve that is adapted to extend through the gears of the sharpening elements and showing the upper end of a hub secured to the sleeve by a set screw.

Figure 10 is a sectional plan through the sharpening elements taken on line 10—10 of Fig. 3 with other parts omitted.

Figure 11 is a detail illustrating a weight formed to provide the lower support of the sliding elements in the lower end of the sharpener.

Referring now to the drawings wherein like reference characters denote corresponding parts the improved pencil sharpener of this invention

includes an elongated casing substantially rectangular shaped in cross section having a rear wall 10, sharpening cutters 11 and 12 journaled on pins 13 and 14, the lower ends of which are held in a slider 15 and the upper ends in arms 16 and 17 of a sleeve 18, and gears 19 and 20 positioned to coat with gear racks 21 and 22, respectively.

The casing is provided with a base 23 and a front wall 24, which is connected to the base with a sloping section 25 is provided with an overhanging flange 26 that may be used as a pull for opening the desk drawer or to cover the exposed edge of the desk or the like and, as illustrated in Fig. 4 the front wall 24 is connected to the rear wall 10, at one end by a web 27 and that at the other by a cover plate 28 that is secured to ears 29 in the end of the casing by screws 30.

The upper edge of the rear wall 10 is provided with an inwardly extended flange 31 having spaced longitudinally disposed grooves 32 and 33 therein and washers 34 and 35, as shown in Figs. 6 and 7, and which are positioned on the sleeve 18 are positioned to travel in these grooves with the opposite sides of the washers in grooves 36 and 37 in an inwardly extended flange 38 on the front wall 24.

The rack is positioned in the flange 38 of the front wall 24 and the gear 19, which is journaled on the sleeve 18 is positioned to mesh with the rack 21. The rack 22 is formed in the flange 31 of the rear wall 10 and this rack is positioned between the grooves 32 and 33 and washers 34 and 35, mounted on the sleeve 18 are positioned with the edges extending into the grooves 32 and 33 and with the edges on the opposite side extending into grooves 36 and 37 of a flange 38 on the upper end of the front wall 24.

The gear rack 21 which is positioned above the groove 36 and upper washer 34 is positioned to mesh with the upper gear 19 and the gear rack 22, in the flange 31 is positioned to mesh with the gear 20 on the opposite side of the housing.

The arms 16 and 17 in which the upper ends of the pins 13 and 14 are carried extend downwardly from the lower end of a hub 39 on the lower end of the sleeve 18 and as the sleeve is rotated by the gears the arms 16 and 17 with the cutting elements 11 and 12 spin around the point of a pencil, shaving the point as illustrated in Fig. 2.

The sleeve 18 is provided with a lower hub 39 which provides a shoulder for the lower washer 35, and the upper part of the sleeve is formed with teeth 40 that coat with latch elements on the gears 19 and 20.

The latch elements are similar to corresponding elements used in window shade rollers and, as illustrated in Fig. 4 the gear 19 is provided with pawls 41 and 42 that are mounted on pins 43 and 44 and the pawls are urged inwardly against the ratchet teeth 40 by springs 45 and 46 respectively. As the element is moved toward the right, as indicated by the arrow 47 the gear 19 will rotate in a clockwise direction and the pawls 41 and 42 will grip the teeth 40 and rotate the cutters 11 and 12 in a clockwise direction.

Likewise pawls 48 and 49 pivotally mounted by pins 50 and 51, respectively on the gear 20 and resiliently held by springs 52 and 53 rotate the cutting elements in a clockwise direction when the element is moved toward the left or in the direction of the arrow 54.

In this movement pinions 55 and 56 on the lower ends of the pins 13 and 14 of the cutters 11 and 12 mesh with the internal gear 57 in a slider 58 and, thereby rotate the cutting elements.

The internal gear 57 is formed in a ring 59, as illustrated in Fig. 1 and the ring is secured to the slider 58 by screws 60 and 61. The base 15 of the cutting elements is suspended from the hub 39 of the sleeve 18 by arms 62 and 63 and the hub 39 is secured to the sleeve 18 by a set screw 65.

The slider 58 is slidably mounted in the lower part of the casing with the edges held in longitudinally disposed grooves 66 on the inner surface of the rear plate 10 and 67 on the inner surface of the front plate 24 respectively. The front plate 24 may be provided with an opening 68 through which a screw driver may be inserted to turn screw 69 into a panel 70, that may be the inner surface of the end of a desk drawer, or the side of a desk or desk top.

The pencil sharpener may also be provided with a heavy base 71 having a slot 72 in the upper surface by which the base may be formed in the lower end of the casing to provide a weight for the sharpener when it is desired to use the device on a desk or a table as a paper weight or the like. It will be understood that the weight may be of any shape or design and may be formed in or attached to the casing in any suitable manner.

With the parts arranged in this manner a pencil, as indicated by the numeral 73 is inserted in the upper end of the sleeve 18, as illustrated in Fig. 2 and by moving the pencil along the slot 74 between the flanges 31 and 38 at the upper end of the casing the pencil will be sharpened. With the latch elements formed in this manner and particularly as illustrated in Figs. 4 and 5 the pencil may be moved in either direction and may be moved back and forth until sharpening thereof is complete.

It will be understood that modifications may be made in the design and arrangements of the parts without departing from the spirit of the invention.

What is claimed is:

1. A pencil actuated pencil sharpener comprising an elongated casing having a slot in the upper surface, pencil sharpening elements rotatably and slidably mounted in the casing, said sharpening elements having a pencil receiving opening therein, a pair of gear racks mounted in opposite sides of the casing and with one gear rack positioned in a plane above the other, pinions mounted on said sharpening elements also with one above the other and positioned to mesh with the gear racks for actuating the said sharpening elements to sharpen a pencil therein as the elements slide in the casing, and latches positioned whereby the pinions are actuated for rotating the elements in a clockwise direction as the said sharpening elements are actuated in both directions, and means rotating cutting elements in said sharpening elements.

2. A pencil actuated pencil sharpener, comprising an elongated casing having a slot in the upper surface, pencil sharpening elements rotatably and slidably mounted in the casing, said sharpening elements having a pencil receiving opening therein, longitudinally disposed gear racks positioned in the upper part of the casing, gears carried by the said sharpening elements meshing with said gear racks, and suitable latch elements actuating the sharpening elements by the gears whereby the sharpening elements rotate in the same direction with the said elements traveling in both directions of the casing.

3. In a pencil actuated pencil sharpener, the combination which comprises an elongated casing substantially rectangular shaped in cross sec-

tion and having an open slot in the upper end, said casing having gear racks in both sides of the slot and positioned in the upper end, pencil sharpening elements slidably mounted in the casing, gears on said sliding elements meshing with the gear racks, latches in the gears for rotating the sharpening elements in one direction with said elements traveling in both directions of the casing, a plate slidably mounted in the lower part of the casing, means journaling the lower ends of the sharpening elements in the said plate, and means rotating cutting elements in the sharpening elements as the sharpening elements are rotated, said sharpening elements having pencil receiving openings therein.
